TOOTHBRUSH RACK

Warren Stansberry, Grand Haven, Mich., assignor to Peerless Novelty Company, Grand Haven, Mich., a corporation of Michigan

Filed Nov. 3, 1960, Ser. No. 62,716

Term of patent 14 years

(Cl. D4—3)

FIG. 1

FIG. 2

FIG. 1 is a front perspective view of a toothbrush rack embodying my new design.

FIG. 2 is a top plan view thereof.

FIG. 3 is a vertical cross sectional view thereof taken on lines III—III of FIG. 2.

FIG. 4 is an end view thereof.

I claim:

The ornamental design for a toothbrush rack, substantially as shown.
